UNITED STATES PATENT OFFICE.

HERMAN F. DERNELL, OF ATHENS, NEW YORK.

ICE-PLOW.

SPECIFICATION forming part of Letters Patent No. 297,236, dated April 22, 1884.

Application filed March 1, 1884. (No model.)

To all whom it may concern:

Be it known that I, HERMAN F. DERNELL, a citizen of the United States, residing at 5 Athens, in the county of Greene and State of New York, have invented certain new and useful Improvements in Ice-Plows, of which the following is a specification.

My invention relates to that class of plows used for cutting ice; and it consists in constructing and securing the adjustable cutters and their bearing-plates so as to permit ready adjustment of the cutters, and hold them with a spring-pressure upon their bearings.

In the drawings, Figure 1 is a sectional elevation of an ice-plow, showing my improvements. Fig. 2 is a plan of Fig. 1. Fig. 3 is a detached view, showing a cutter and supporting or bearing plate.

The beam A of the plow is made in any suitable manner, as shown. It consists of the parallel plates *a a*, to which are secured the usual handles, B.

The cutters C consist each of a steel blade bent to about a regular curve, and having a bearing at the rear edge upon the curved forward edge of a supporting-plate, D, of any suitable form and construction, bolted or secured rigidly to the beam A. The bearing-edges of the cutter and plate are tongued and grooved, to prevent lateral displacement of the cutter from its bearing. Thus the cutter-bar has either a V-groove in the rear edge and the plate has a corresponding projection at the front edge, as shown, or there is a dovetailed rib, *s*, upon the bearing-edge of the plate D, and a corresponding groove in the cutter. The curve of the back edge of the cutter C is somewhat greater than that of the bearing-edge of the support D, and the cutter is forced back against its bearing, so as to bend under the pressure thus applied, thereby having a spring bearing against the edge of the plate D, which secures a much firmer frictional contact than is possible where the bars are of the same curve as the plates, as heretofore, thus preventing the cutter slipping under the pressure or impact upon the point, and obviating all tendency to slip or be jarred from contact with the plate under the action of lateral blows. The cutters are suitably secured

in the positions shown, and the plow is used in the ordinary manner, any wear of the cutting-point being compensated for by setting the cutter farther downward on its bearings.

Any suitable appliances may be employed 55 for springing in the cutter-bar firmly upon its seat and securing it in place and releasing it for adjustment. Thus a wedge, E, may be inserted between the sides of the beam, the front edge of the cutter-bar, and the rear inclined edge of the preceding plate D, or any inclined bearing upon the beam, and a nut, *d*, bearing on the beam and receiving a screw-rod, *i*, projecting from the wedge, may be the means of lifting the latter to jam the bar tightly against its bearings.

Instead of a nut and screw-pin, a transverse bolt, *h*, with an eccentric portion, *e*, may be arranged to be turned to bring each eccentric portion against the block E; or any other 70 available tightening device may be used.

I have shown two cutters and two supporting backing blades; but any desirable number of cutters and supports may be connected with the beam A.

Without limiting myself to the precise construction and arrangement of the parts shown, I claim—

1. The combination, in an ice-plow, of a beam, one or more plates or supports, D, connected thereto and having forward curved edges, and cutter-bars C, with bearing-edges conforming to curves slightly greater than the edge bearings upon the supports, substantially as described.

2. The curved cutter-bars having their rear bearings upon the forward edges of supporting-plates having greater curves and secured to the beam, in combination with devices for bending the cutter-bars back against their 90 bearings, substantially as described.

3. The combination of the cutter-bars and supporting-plates, the curve of the edges of the bars differing from that of the edges of the plates, and the bearings of the bars and plates 95 having corresponding grooves and projections, substantially as described.

4. The combination of the beam A, differently curved cutter-bar C, wedge E, and means for forcing the latter between the rear 100

inclined edge of the plate D and the edge of the cutter, substantially as described.

5. The combination of the beam A, plate D, having an inclined rear edge, curved cutter-bar C, wedge arranged between the rear edge of the plate and the adjacent cutter-bar, screw-pin e upon the wedge, and nut d, substantially as described.

6. The combination of the plate D and bar C, one having a dovetailed edge rib fitting a cor-

responding groove in the other, substantially as described.

In testimony whereof I have signed my name to this specification in the presence of two subscribing witnesses.

H. F. DERNEll.
